VALVED CONSTRUCTION FOR TORCH
HANDLES AND METHOD OF MAKING
THE SAME

Alfred F. Chouinard and Mitchell A. Tylutki, Chicago, Ill., assignors to National Cylinder Gas Company, Chicago, Ill., a corporation of Delaware

Application June 2, 1945, Serial No. 597,300

6 Claims. (Cl. 277—46)

1

This invention relates in general to burners for flame blasting and other analogous purposes, and having one or a series of outlets where the flame or flames are produced from a combustible gas such as acetylene, and a combustion supporting gas, which are premixed and delivered thereto. Constructions of this type usually have a handle which at one end supports the burner, and two hoses for the separate gases are connected thereto at the rear or opposite end.

The main object of the invention is to provide an improved hose connecting member for the rear of the handle, and an improved method of making such a member. In our improved construction and in carrying out our improved method said member is formed of a plurality of parts which may be made of bar stock rather than a casting, and therefore are easy and inexpensive to machine before assembly, and may be easily assembled. Two of these parts carry the controlling valves for the gases, and are so positioned that the valves may be easily and independently operated. A third part serves to connect the other two parts to the handle, and is provided with a centrally disposed connection for a conduit through which water may be delivered for circulation through the handle, to cool the latter. The gas hoses are connected below the axial center of the handle to give the handle a balance, making it easy to hold the burner in proper position in respect to a work surface. Other features and advantages will be apparent from the drawing, or will be pointed out hereinafter.

In the drawing:

Fig. 1 is a perspective view of one embodiment of our improved construction.

Fig. 2 is a top plan view of the handle, portions being broken away.

Fig. 3 is a side elevation of the handle, portions being broken away.

Fig. 4 is an end view, for instance in the plane of the line 4—4 of Fig. 3.

Fig. 5 is a section through one valve, and on the line 5—5 of Fig. 4.

Fig. 6 is a section on the line 6—6 of Fig. 4.

Fig. 7 is a face view of the base or connecting member, and

Fig. 8 is an edge view of the member shown in Fig. 7.

In the specific construction illustrated, there is shown a burner 10 which has a row of outlets 11 to which the gas mixture is delivered, and at which there is formed a row of closely spaced flames. The burner is also shown as having a second row of outlets 12 for jets of quenching

2

water. The details of the burner itself have not been illustrated, as it forms no novel part of the present invention. It may be of the type shown in the Mott and Whaley Patent 2,218,827, or of any other suitable type.

The burner is secured to and carried by a handle section 13 which may be a tube encircling the pipe 14 delivering the gas mixture to the burner, and if quenching jets are employed, as at the outlets 12, the handle may serve to conduct water to the burner and around the inner gas mixture pipe 14 to keep the gas mixture cool. Water may be delivered to this handle section through a hose 15.

15 The rear end of the handle section 13 is detachably connected to a rear handle section 16 which may be held in the hand of the operator, or held by use of a torch clamp. As shown, a nut 17 is screwed onto an end piece 18 of the handle section 13 to hold in place a gas mixer 19 for bringing the oxygen and acetylene in the proper relative proportions, and under the desired pressure. This mixer 19 may be screwed into the handle section 13 to connect with pipe 14.

20 Our invention relates primarily to the construction of the parts employed at the rear of the handle section 16, hereinafter referred to as the handle, as it is the part which is grasped or held in the operation of the torch. Instead of making these parts of a single casting, which would require expensive patterns and expensive jigs for machining, we make them of three pieces of bar stock which may be easily machined before assembly, and then brazed together. These parts include a part 20 shown in Figs. 7 and 8, and hereinafter referred to as a base, and two parts 35 and 36, hereinafter referred to as valve casings.

25 The base 20 is in the form of a plate with a large boss 21 on one side adapted to snugly fit into the tubular handle 16 and be secured thereto in any suitable manner. On the other or outer side of the plate are two large grooves or channels 22 and 23 disposed at an acute angle to each other, and presenting cylindrical surfaces. The two grooves may be disposed quite close together at one edge of the plate, as shown at the lower edge of Fig. 7, and may be spaced some distance apart at the opposite edge, as shown at the upper edge of Fig. 7, so as to leave a substantially flat triangular surface 24 therebetween. Two parallel holes 25 and 26 are bored into the boss 21, and two holes 27 and 28 are bored into the surfaces of 30 the grooves or channels 22 and 23 to intersect

the holes 25 and 26 respectively, as shown in Fig. 6.

If the handle 16 is to be water cooled, two holes 29 and 30 are bored through the plate, in the triangular portion 24 between the grooves 22 and 23, the upper one being for the inflow of water from a hose 31 to a pipe 32 within the handle, and the other for the outflow of water used in cooling the handle.

The two valve casings 35 and 36 may be similar in shape and size, but made as right hand and left hand, so far as concerns the gas outlet ports which register with the passages 27 and 28. Each valve casing is made of a single piece of cylindrical bar stock, and has an outer surface of the same curvature as the grooves 22 and 23, so that they may be brazed in place in said grooves and thus be disposed at an angle to each other, as shown particularly in Fig. 4.

Each valve casing has a hole drilled from end to end to form a valve chamber 37 and a valve seat 38, and is provided with a valve member 39 swiveled on the end of a valve stem 40, which latter is threaded in a gland or bushing 41 provided with a packing 42 and a packing nut 43. The outer end of the valve stem has a suitable handle 44.

Below the valve seat there is an inlet port 45 into which a nipple 46 may be inserted to abut against a flattened face 47, brazed in place, and adapted for connection to a gas supply hose 48.

From the valve chamber above the valve seat there is a port 49 for registering with the corresponding passage 27 or 28 when the valve casing is brazed to the base member 20.

It will thus be seen that the valve casings, being at an angle to each other, permit the hose connections 46 to be relatively close together, have the valve handles 44 spaced sufficiently far apart to permit easy operation of either valve, and provide adequate space between the valve casings for the cooling water connection, if such be employed. All of the machining of the parts 20, 35 and 36 may be effected before the assembly.

The gases delivered through the two hoses 48 and the two valve casings may be conducted to the mixer 18 by suitable pipes in the handle 16. As shown in Figs. 2 and 3, acetylene may flow through a pipe 50, and oxygen through a pipe 51, to passages in the block 18 in which the mixer 19 is mounted. This block may have a V-passage 53, to one leg of which the water pipe 32 may be connected. Thus, water delivered through the hose 31 may be led to the V-shaped passage 53 to cool the block 18, and then discharged into the handle 16 to flow back and out through the lower port 29, to which a hose 31' may be connected if desired.

It will be obvious that various changes may be made in the details of construction, and the drawing illustrates merely one embodiment of the invention. As previously indicated, the ports 29 and 30 of the base member and pipe 32 in the handle may be omitted if cooling of the handle is not desired or is not considered necessary. Also, the hose 15 may be omitted if it is not desired to deliver quenching jets of water to the workpiece.

Having thus described our invention what we claim as new and desire to secure by Letters Patent is:

1. A multiple valved hose connecting member for torch handles, including a base section having one side adapted to extend into and be secured to the rear end of a torch handle, and having in the opposite side a pair of grooves at an

acute angle to each other, and passages leading from said grooves to the first mentioned side of said section, and a pair of valve casings disposed in said grooves and welded to said base section, each valve casing being provided with an inlet in the side away from said base, and an outlet in the side disposed in said grooves and registering with the corresponding one of said passages, a valve movable lengthwise of the valve casing, said inlets being at the ends of said valve casings which are close together, and said valves having handles at the end of said casings which are farthest apart.

2. The method of forming a hose connecting valved unit for torch handles, including the steps of shaping a circular disc-like base member from bar stock to form a boss on one side and grooves at an acute angle to each other in the opposite side, forming a passage leading from each groove to the opposite side through the boss, forming a pair of cylindrical valve blocks from bar stock, each with a portion of the peripheral surface thereof conforming to said groove and with a valve seat therein, an inlet adjacent to one end below the valve seat and a substantially diametrically opposite outlet above the valve seat, welding said valve blocks in said grooves with the end portions having the inlets disposed adjacent to each other and the outlets registering with the passages through said base member.

3. A hose-connecting valved unit for a torch handle, including a circular disc-like base member having a coaxial boss on one surface and adapted to be extended into and secured to a torch handle, and transverse grooves at an angle to each other on the opposite surface, a pair of passages each leading from a separate one of said grooves and through said boss, a pair of pieces of bar stock each having a valve chamber and a valve seat therein, a lateral outlet passage leading from said valve chamber above said valve seat and a lateral inlet passage below said valve seat, said bar stock pieces being welded in and along said grooves with the outlet passages registering with said passages in said base member, and with the inlet passages substantially parallel to each other and on the side away from said disc-like member, and valves in said pieces and movable toward and from said valve seats.

4. A hose-connecting valved unit for a torch handle, including a circular disc-like base member having a substantially cylindrical coaxial boss on one surface and adapted to be extended into and secured to a torch handle, and transverse grooves at an angle to each other on the opposite surface, a pair of passages one leading from each groove and through said boss, a pair of pieces of bar stock each having a valve chamber and a valve seat therein, a lateral outlet passage leading from said valve chamber above said valve seat, and a lateral inlet passage below said valve seat, said bar stock pieces being welded in and along said grooves with the first mentioned passages thereof registering with said passages in said base member, and with the second mentioned passages on the side away from said disc-like member, valves in said pieces and movable toward and from said valve seats, and handles for said valves and at the ends of said bar stock pieces which are farthest apart.

5. The method of forming a hose-connecting valved unit for a torch handle, including the steps of shaping a circular disc-like base member from bar stock to form a circular coaxial boss on

one surface and transverse grooves at an angle to each other on the opposite surface, boring a pair of passages each leading from a separate one of said grooves and through said boss, boring an axial passage into each of a pair of pieces of bar stock to form a valve chamber and a valve seat therein, boring into each of said pieces a lateral passage leading to said first mentioned passage above said valve seat, boring into each of said pieces a lateral passage below said valve seat, the two passages of each piece being at an angle to each other, and welding said bar stock pieces into said grooves with said first mentioned passages at an angle to each other and registering with said passages in said base member, and with the second mentioned passages substantially parallel to each other and on the side away from said disc-like member.

6. The method of forming a hose-connecting valved unit for a torch handle, including the steps of shaping a circular disc-like base member from bar stock to form a circular coaxial boss on one surface and transverse grooves at an angle to each other on the opposite surface, boring a pair of passages each leading from a separate one of said grooves and through said boss, boring an axial passage into each of a pair of pieces of bar stock to form a valve chamber and a seat

therein, boring into each of said pieces a lateral passage leading to said first mentioned passage above said valve seat, boring into each of said pieces a lateral passage below said valve seat, and welding said bar stock pieces into said grooves with said first mentioned passages at an angle to each other and registering with said passages in said base member, and with the second mentioned passages on the side away from said disc-like member.
